SLICING MACHINE WITH STATIONARY
KNIFE AND RECIPROCATING CARRIER

William F. Beavers, Belen, N. Mex.

Application February 17, 1950, Serial No. 144,777

4 Claims. (Cl. 146—168)

1

This invention relates to a slicing machine particularly adapted for the slicing of potatoes and like foods in attractive shapes, but usable also for ordinary or plain slicing as well.

One important object of the invention is to provide a slicing machine of the type stated adapted to slice potatoes and similar foods into waffle-like slices.

Another important object is to provide a slicing machine of the type stated that will perform fancy slicing operations with speed and ease.

Still another object is to provide a slicing machine that can be manufactured at relatively low cost but which will be quite efficient and durable.

Still another object is to provide a slicing machine which, though capable of manufacture at no greater cost than conventional slicers nevertheless can be used for all the plain slicing functions discharged by a conventionally constructed slicer, as well as the slicing of articles to fancy or ornamental shapes.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawing in detail, Fig. 1 is a front elevational view of the improved slicing machine.

Fig. 2 is a top plan view.

Fig. 3 is a section taken substantially on line 3—3 of Fig. 2.

Fig. 4 is a rear elevational view, portions being broken away.

Fig. 5 is an enlarged fragmentary detail perspective view of a portion of the food carrier showing a dog and bumper rail embodied in the device.

Fig. 6 is a fragmentary enlarged detail perspective view of the supporting carriage for the food carrier and a part of the slideway on which said supporting carriage is mounted.

Referring to the drawing in detail, I provide a flat base 1 which is here shown as a substantially rectangular, heavy plate of metal material, although the plate can be of other shapes or materials, the base 1 being formed at its ends with the rearwardly extended wings 2 in which are threaded the screws 3 that fixedly connect to said wings 2 the opposite ends of an elongated guide rail 4 here shown as rectangular in

2

cross section, said guide rail 4 extending into a recess 5 formed in the bottom end of a depending guide finger 6 that is formed integrally upon one end of a tubular carriage 7. Formed integrally upon the other end portion of said carriage 7, and extending under the carriage, is a boss 8 to which is detachably connected the horizontally extending handle 9, by means of which the user may conveniently grasp the carriage for reciprocating the carriage upon the slide rail or track 10 extending through the bore of the tubular carriage and secured at its ends to the upstanding supports 11 mounted upon the ends of the base 1, and supporting the slide rail 10 in elevated position above the base.

The opposite ends of the tubular carriage 7 may of course be provided with rubber bumpers or the like for the usual well known purpose, and this has been considered sufficiently obvious as not to require special illustration.

From what has been so far described, it will be seen that upon the rear portion of the base 1, I provide a slideway upon which is mounted for slidable reciprocating movement a supporting carriage, that is held against wobbling during its travel by a suitable guide means. In this connection, although I have illustrated the carriage as being reciprocable manually, I believe it is quite possible to give reciprocating movement to said carriage from end to end of its elongated slideway by any of various well known power operated devices, not shown.

Mounted rigidly upon the top of the carriage 7, and extending laterally and horizontally therefrom, is a T-shaped bearing plate 12, upon which are rigidly mounted the bearing sleeves 13, aligned crosswise of the slide rail 10, as readily seen from Figs. 3 or 6. Extending through the bearings 13 is a rock shaft 14 to the opposite ends of which are fixedly secured the short supporting arms 15 each of which has at its upper end an angular recess 16 receiving the angular corner portion at each end of a food carrier 17 L-shaped in cross section, said carrier 17 being rigidly connected to the respective supporting arms 15.

The outer end of the food carrier 17 is provided with the end wall 18, while slidably mounted in the inner end of said carrier is the presser foot 19 adapted to press a potato or other article of food to be sliced forwardly against a cutting table in a manner to be made apparent herein-after.

The presser foot 19 is secured to one end of a follower rod 20 around which is positioned the

compression spring 21 one end of which abuts against the presser foot 19, the other end of said spring abutting against the sleeve 22 interposed between the spring and end wall 18, a take-up nut 23 being threaded upon the rearwardly projected end of the follower rod 20, for the purpose of adjusting the spring tension.

Secured to the corner portion of the carrier 17 at the inner end of said carrier and extending downwardly from said carrier and obliquely to the carrier walls is a dog 24 that is rigid with the carrier, and which is formed in the present instance as a short bar the free lower end of which is formed with the angular end surfaces 25, either of which is slideable along a bumper rail 26 extending parallel to the slide rail 10 and rigidly mounted upon and above the base 1 by means of supports 27.

The bumper rail 26 is shorter than the slide rail 10, terminating at both ends well short of the adjacent end of the slide rail 10, as best seen from Figs. 1 and 2. From what has been described it may be observed that the food carrier is mounted for rocking or oscillative movement upon the sliding carriage. During travel of the sliding carriage in one direction, one wall 28 of the food carrier will be horizontally positioned, while the outer wall 25 is vertically positioned. The carrier will be held against movement from this position because the dog 24, during said slideable travel of the carrier in one direction, is in engagement with the bumper rail 26. Rocking movement of the food carrier in an opposite direction is limited by means of either one of a pair of adjusting screws 29 threaded in the plate 12, and limiting oscillating movement of the food carrier in opposite directions.

As the carriage 7 reaches the end of its travel in one direction, the dog 24 slides off one end of the bumper rail 26, and drops downwardly just enough to cause it to be engaged by said end of the bumper rail 26 when the carriage 7 begins its travel in a return direction. As a result, the food carrier is instantaneously rocked to its other extreme position, with the wall 25 of the food carrier now being horizontal and the wall 26 being vertical, the carrier thus in effect being rocked through ninety degrees from one extreme position to another, and being given this movement each time the carriage 7 reaches the limit of its slideable travel past the cutting means of the machine, and begins its return travel.

The supports 27 for the bumper rail 26 are rigidly attached in any suitable manner to the base 1, as for example by screws 28.

Rigidly mounted by means of supporting arms 30 in elevated position above the base 1 is a flat table 31 along one side of which is mounted the elongated vertically positioned side wall 32, between the ends of which is formed the space 33 in which is adjustably mounted the vertically positioned cutter plate 34 detachably and rigidly connected to the upstanding arm 35, rigid at its lower end with the horizontally extending foot 37 sliding in the guide 38 mounted upon the base 1. A clearance space 36 for said upstanding arm 35 is formed in the table 31, to permit room for adjustment of the supporting arm. Such adjustment is achieved in the present instance by means of the advancing screw 39 formed at one end with a knurled head or the like, and swiveled at its other end in the cutter support 35, said advancing screw 39 being threaded in the upstanding bracket 40 mounted

upon the angle member 41 that is secured in any suitable manner to the base 1.

The cutter 34 in the present instance is formed as a rectangular plate having the transverse corrugations, the opposite edges of said plate being sharpened so as to cause slicing of the article of food upon travel of the carrier in both directions.

The form of cutter illustrated, in this connection, is a form particularly adapted for the slicing of potatoes or similar articles of food in waffle-like shapes. However, various forms of cutting knives 34 can be detachably secured to the upstanding arm 35, and these forms can be, for example, plain cutter knives, cutter knives having closely spaced corrugations for julienne potatoes, cutter knives having waved cutting edges, etc.

In use, the advancing screw 39 is operated so as to provide the desired space between the cutter 34 and the stop wall 32. Obviously, the greater this space, the thicker will be the slice.

In any event, the potato P is positioned as illustrated, and the user simply gives reciprocating travel to the carrier 7 to its opposite extreme positions, as a result of which the potatoes will be cut to waffle-like shapes or slices. On movement of the carrier in one direction, with the side wall 26 positioned horizontally, a slice having a corrugated surface will be cut from the potato P. When the carrier reaches the end of movement in one direction, the food carrier will be rocked to its other extreme position, turning the potato P ninety degrees. As a result, when the potato moves back past the cutter, a slice will now be cut off one surface of which is corrugated at right angles to the other surface. If the slice is cut off so as to be quite thin, a waffle-like, attractive shape will be given the slice, and if the slice is thin enough, the slice will be formed with a grid-like arrangement of openings extending fully therethrough. These slices may then be readily French fried and provide an attractive way of serving the potatoes or other articles of food cut. As the carriage 7 continues its reciprocating movement back and forth past the cutter, continued slicing of the potato results, with each slice having its corrugations on one face at right angles to the corrugations on the opposite face.

If it is desired that ordinary slicing operations be carried out, it is necessary only to replace the cutter 34 with a plan cutter, that is wholly flat, and this will cause the slices to be wholly conventional, thus to permit the slicer to be used for slicing luncheon meats or the like.

What is claimed is:

1. A slicing machine including a base; a carriage slidably reciprocable thereon; a cutter stationarily mounted on the base and disposed intermediate opposite extreme positions between which the carriage is shiftable; a food carrier rockably mounted on the carriage; a bumper rail rigid with the base and paralleling the line of reciprocating movement of the carriage, said rail terminating at opposite ends short of the extreme positions between which the carriage is reciprocable; and a dog rigid with the carrier, said dog being shiftable gravitationally into the path of the bumper rail and being normally held against said shift by the bumper rail, said dog gravitating into the path of the respective ends of the bumper rail upon shifting of the carriage to its respective extreme positions, for engagement of the dog by the bumper rail to rock the

food carrier at the beginning of return movement of the carriage toward the cutter.

2. A slicing machine including a base; a carriage slidably reciprocable thereon; a cutter stationarily mounted on the base and disposed between opposite extreme positions to which the carriage is shiftable; a food carrier mounted on the carriage to rock in a vertical plane; stops on the carriage limiting rockable movement of the carrier through approximately 90° in either direction; a bumper rail rigid with the base and paralleling the line of reciprocation of the carriage, said rail terminating at opposite ends short of the extreme positions between which the carriage is reciprocable; and a dog rigid with the carrier and swingable in a vertical plane, said dog sliding upon and being elevated against gravitational swinging movement by the bumper rail during shifting of the carriage past the cutter in either direction, said dog sliding off opposite ends of the bumper rail on movement of the carriage to its respective extreme positions and shifting gravitationally into the path of the bumper rail, for engagement by the ends of the bumper rail to rock the carrier from one of its extreme positions to the other at the beginning of return movement of the carriage.

3. A slicing machine including a base; a carriage slidably reciprocable thereon; a cutter stationarily mounted on the base intermediate opposite extreme positions between which the carriage is reciprocable; a food carrier oscillably mounted on the carriage and swinging in a vertical plane; stops on the carriage limiting oscillation of the carriage between extreme positions spaced apart approximately 90°; a bumper rail rigid with the base and paralleling the line of reciprocation of the carriage, said bumper rail terminating at opposite ends thereof short of the extreme positions between which the carriage is reciprocable; and a dog rigid with the carrier and swinging in a vertical plane, said dog extending through and below the center of oscillative movement of the carrier and being disposed obliquely to the bumper rail in the respective extreme positions of the carrier, said dog slidably contacting and being held against gravitational swinging movement by the bumper rail during movement of the carriage between its respective extreme positions, said dog gravitating into the path of the ends of the bumper rail at opposite ends of the line of travel of the carriage, for engagement by said ends on return movement of the carriage, to rock the carrier from one of its extreme positions to the other.

4. A slicing machine including a base; a carriage slidably reciprocable thereon; a cutter stationarily mounted on the base intermediate opposite extreme positions between which the carriage is reciprocable; a food carrier oscillably mounted on the carriage and swinging in a vertical plane; stops on the carriage limiting oscillation of the carriage between extreme positions spaced apart approximately 90°; a bumper rail rigid with the base and paralleling the line of reciprocation of the carriage, said bumper rail terminating at opposite ends thereof short of the extreme positions between which the carriage is reciprocable; and a dog rigid with the carrier and swinging in a vertical plane, said dog extending through and below the center of oscillative movement of the carrier and being disposed obliquely to the bumper rail in the respective extreme positions of the carrier, said dog slidably contacting and being held against gravitational swinging movement during movement of the carriage between its respective extreme positions, said dog gravitating into the path of the ends of the bumper rail at opposite ends of the line of travel of the carriage, for engagement by said ends on return movement of the carriage, to rock the carrier from one of its extreme positions to the other, said dog being formed as a finger the free, lower end of which is formed with angularly related beveled end surfaces, one of said end surfaces being in slidable contact with the bumper rail during shifting of the carriage between extreme positions, the other forming an abutment to be engaged by an end of the bumper rail on return movement of the carriage.
